(57) **CLAIM**

The ornamental design for a motor vehicle body, as shown and described.

DESCRIPTION

FIG. 1 is a front and left side perspective view of a motor vehicle body, in accordance with our new design, showing the body with doors in a lowered or closed position;

FIG. 2 is a left side elevational view of the motor vehicle body shown in FIG. 1, the right side being identical thereto;

FIG. 3 is top plan view of the motor vehicle body shown in FIG. 1;

FIG. 4 is a bottom plan view of the motor vehicle body shown in FIG. 1;

FIG. 5 is a rear elevational view of the motor vehicle body shown in FIG. 1;

FIG. 6 is front elevational view of the motor vehicle body shown in FIG. 1; and,

FIG. 7 is a front and left side perspective view of the motor vehicle body shown in FIG. 1, showing the body with doors in a raised or open position.
